UNITED STATES PATENT OFFICE.

GUSTAVE M. GOLDSMITH AND CARL P. BARTELS, OF HAMILTON, OHIO, ASSIGNEES TO
THE MOSLER SAFE COMPANY, OF HAMILTON, OHIO, A CORPORATION OF NEW YORK.

LOCKING DEVICE.

Application filed June 30, 1921. Serial No. 481,474.

To all whom it may concern:

Be it known that we, GUSTAVE M. GOLDSMITH and CARL P. BARTELS, citizens of the United States, residing at Hamilton, Butler County, Ohio, have invented certain new and useful Improvements in Locking Devices, of which the following is a specification.

The present invention relates to locking devices and more particularly relates to a lock which is particularly well suited for application to safety deposit boxes, although the lock is in no wise limited in its application to lock boxes and is suited for broad application.

Many locks are so arranged and so mounted that it is possible to strip them from the door or other member upon which they are mounted by pounding inwardly upon the key tube from the outside, and when the lock is so removed, its bolt will, in consequence, be removed from its locking position in its socket, and the door may then be opened without further interference from the bolt or lock. It is one of the objects of our invention to provide a lock having one or more bolts so arranged that when the main part of the lock is stripped from the door or other element upon which it is mounted, so as to fall therefrom, the bolt bars or parts thereof will nevertheless be maintained in locking position in their sockets and will prevent the door from being opened. In other words, our invention comprises the provision of a lock so constructed and arranged that when mounted in a box and locked access may not be had to the interior of a box as a result of stripping the main portion of the lock therefrom. A further object of our invention is to provide a bolt so arranged and constructed that when the main part of the lock is stripped from the door or other element upon which it is mounted, the bolt or a part thereof will not only be maintained in locking position in its sockets, but will also move automatically into a position which makes it difficult to tamper with the bolt by means of a wire or instrument inserted through the hole provided in the door for the key seat of the lock. Other objects will be in part obvious and in part pointed out hereinafter.

In accordance with our invention we provide a lock having a slidable bolt. The bolt is normally adapted to be slid into or out of locking position in the usual manner by op-

erating a key, but differs from the usual one-piece bolt construction in that the bar consists of two pieces, arranged end to end, and is so connected that normally the bolt may be slid back and forth by operating the key, but, when the main part of the lock is moved inwardly of a door or other element on which it is mounted, the two parts of the bolt will separate, and the outer part of the bolt which is in its socket will remain therein and still function and keep the desired elements locked together. The outer portion of the bolt is preferably provided with a slot through which is mounted a bolt or screw engaging the door or other element on which the lock is mounted, the screw having a head larger than the width of the slot, thus permitting the desired sliding movement of the bolt into locked or unlocked position and also cooperating to maintain the bolt in locking position should the main part of the lock be removed. The connection between the two parts of the bolt may comprise a pin carried at one end on one of the parts at one end and adapted to engage within a perforation in the other part at its adjacent end. These abutting ends may be properly rabbed. The outer end of the bolt, when the main part of the lock is removed, may be arranged to swing about the bolt or screw extending through the slot therein so as to engage suitable stops, which will aid in maintaining that part of the bolt in locking position, or this end of the bolt may be provided with a projection which is adapted to become seated in the socket when this part swings about the bolt. Obviously, our invention may be applied to many types of locks and may be adapted to many uses.

In order that a clearer understanding of our invention may be had, attention is hereby directed to the accompanying drawings illustrating certain embodiments of our invention. Referring to the drawings, Fig. 1 is a horizontal section of a lock box embodying our invention; Fig. 2 is a vertical section of a lock box taken on line 2-2 of Fig. 1; Fig. 3 is a view similar to Fig. 2 showing a modified form of bolt. Similar reference characters designate similar parts throughout the several views of the drawings.

In the drawings we have illustrated our improved lock as being mounted on the outer face of a drawer in a safety deposit box. The construction of the box is similar

to the construction disclosed and claimed in our application for improvements in Lock Box, Serial Number 472,501, filed May 25, 1921. In said application we have described, and in the drawings submitted herewith we have illustrated, a safety deposit lock box which comprises top wall 1, bottom wall 2, side walls 3 and 4 respectively, door 5, hinged in the usual manner, as at 6, to one side 3 of the box, and a lock 7 secured to the rear of the door by means of bolts 8. The key tubes of the lock are shown at 10 and an abutment plate 13 which is shown to comprise the front face of a drawer in the box is shown secured to the side walls 14 and 15, and to the bottom 16 of the drawer by spot-welding or other suitable means. To the inside of wall 3 of the box is firmly secured a plate 20 having a rigid shoulder portion 21 adapted to abut against the rear face of plate 13 along its edge which is near side 3 of the box. Rigid member 22, similar to member 20, is secured interiorly of the wall 4 of the box, and has a similar shoulder or abutment 23 adapted to abut against the rear face of plate 13 along its edge which is near the wall 4. When it is attempted to strip the lock 7 away from the door 5 by pounding or applying pressure to the key tubes 10 the lock 7 will be forced against the rigid plate 13 which in turn is held against inward movement by the shoulders 21 and 23 of the side pieces 20 and 22, thus preventing the lock 7 from being stripped from the door 5 in consequence of the pounding.

In the construction so far described, when the door of the box is opened in the regular manner, the drawer therein is free to be pulled out. A lock 24, which embodies our present invention, is shown to be mounted on the rear face of the plate 13 and is adapted to lock the drawer in the box, so that even after the door of the box has been opened in the regular manner, the lock which is mounted on the drawer must be operated in the regular manner before the drawer may be pulled out. Lock 24, except for its bolt, may be of any one of several usual types which slide the bolt, and may be secured to the inside of the plate 13 in any usual manner, as by means of screws 25, with its key tube 26 extending through a perforation in the plate 13. As shown, the lock 24 is of the type wherein one key operates two oppositely disposed bolts simultaneously to slide the same into and out of locking position. Instead of each of these bolts being in one piece, as is usual, each bolt consists of two parts, 27 and 28 respectively, placed end to end, and severably connected, as by means of a pin 30 on one of these pieces, such as piece 27, which pin is movably seated in a perforation 31 in the abutting piece 28. If desired, pin 30

and perforation 31 may be provided on end portions which are reduced as at 29. The outer severed piece 28 of each bolt is provided with a slot 32 and a screw or bolt 33 is fastened on the plate 13 so as to extend through this slot 32, the screw 33 having a head wider than the width of slot 32. So long as the two pieces of the bolts are connected together, their outer portions 28 are moved by the ordinary operation of the key into and out of locking position, one piece 28 moving into and out of locking engagement behind the shoulder 21 of piece 20 as shown at 34, and the oppositely disposed bolt piece 28 moving into and out of locking engagement behind the shoulder 23 of the piece 22 as shown at 35. The rabbeted portions 29 of the two pieces 27 and 28 of each bolt bar, and the pin connection therebetween, is such that when the main part of the lock 24, including bolt sections 27, are moved inwardly of the plate 13, the outer pieces 28 of the bolts will remain mounted on plate 13, being held thereon by screws 33. The portion of each of the pieces 28 which is inwardly of the screw 33 is heavier than the portion on the other side of screw 33, and when it is freed from bolt section 27, piece 28 will pivot about the bolt 33. In order to maintain the outer end of this bolt portion in locking engagement behind the shoulders 21 or 23 when it is freed from bolt section 27, suitable stopping members may be provided which are adapted to be engaged by and to hold the inner end of these bolt portions 28, preventing the same from sliding or falling out of locking engagement behind the shoulders 21 or 23. These stops may comprise pins 36 suitably positioned on the inner face of plate 13. One possible modification in the construction of the bolts is illustrated in Fig. 3. In this construction the outer portions 28 of the bolt bars have a portion 37 which is adapted to be slid into and out of locking engagement behind shoulders 21 and 23 in the regular operation of the lock, and have another portion 38 which will become seated behind the shoulders 21 and 23 whenever these outer bolt portions 28 have turned about the pivots 33, as when the lock has been removed from the door and portions 28 are free of portions 27. In Fig. 3 the dotted lines indicate the second position of the projection 38 and the outer portion 28 of a bolt bar.

It will be apparent that the lock and bolting means described are such that the box or drawer or other element which is locked thereby may not be opened even though the main part of the lock is stripped from its mounting, and that the portions 28 of the bolts may be so arranged and designed that whenever the main part of the lock is displaced they will automatically move away

from the key tube perforation in plate 13 and into a position where they may not be easily reached or tampered with to effect their adjustment into unlocking position. 5 The lock disclosed is not limited to use in connection with safety deposit lock boxes but may be adapted to many different uses. Also, instead of arranging the bolts to abut behind shoulder members 21 and 23 separate 10 sockets may be supplied for the bolts. It is obvious that many other changes may be made in the above described construction and many apparently widely different embodiments of this invention may be made without departing from the scope thereof, and it is, therefore, intended that all matter contained in the above description or shown in the accompanying drawings shall be interpreted as illustrative and not in a limiting 15 sense.

What we claim is:

1. In a device of the character described, in combination, a drawer, a locking element slidably and pivotally mounted on said 20 drawer, means comprising a lock having a slidable bolt-part severably connected to said element for sliding said element into and out of locking position, said element being arranged to pivot when said connection is severed, and means comprising stops on said 25 drawer positioned to engage said element when it pivots, for maintaining said element in locking position.

2. In a device of the character described, in combination, a drawer and a lock mounted thereon having a locking element slidably and pivotally mounted on said drawer, and means including a severable operative connection between a main part of said lock and said locking element whereby said locking element is maintained in one position on said drawer, said locking element being adapted to pivot into a different position on said door upon the severing of said connection. 35 40 45

3. In a lock box, the combination with a drawer having for its front face a rigid plate, of a lock on the rear side of said plate and having a bolt comprising two pieces severably connected, one of said pieces being slidably and pivotally mounted on the rear side of said plate and maintained by the other bolt piece in one position for sliding movement thereby into and out of locking position, and also being arranged to pivot 50 55 on said plate into another locking position whenever the connection between said two bolt pieces is severed.

This specification signed and witnessed this 27th day of June, 1921.

GUSTAVE M. GOLDSMITH.
CARL P. BARTELS.
